Fig. 6.

FIG. 1 is a perspective view of an electric push button switch showing my new design;

FIG. 2 is a front view thereof;

FIG. 3 is a top view thereof;

FIG. 4 is a perspective view similar to FIG. 1, showing a modification of my switch employing a long actuator button,

FIG. 5 is a front view similar to FIG. 2, but showing the embodiment of the invention of FIG. 4; and

FIG. 6 is a top view similar to FIG. 3, but corresponding to FIGS. 4 and 5.

The dominant features of my design reside in the portions shown in full lines. The bottom is plain, and the sides which are not shown are similar to those which are shown.

I claim:

The ornamental design for an electric push button switch, as shown and described.
